UNITED STATES PATENT OFFICE.

GRANT BEST, OF DETROIT, MICHIGAN, ASSIGNOR TO NYAL COMPANY, OF DETROIT, MICHIGAN, A CORPORATION OF MICHIGAN.

DESIGN FOR A PERFUME-HOLDER.

52,728.

Specification for Design.

Patented Dec. 10, 1918.

Application filed September 28, 1918. Serial No. 256,154. Term of patent 14 years.

To all whom it may concern:

Be it known that I, GRANT BEST, a citizen of the United States of America, residing at Detroit, in the county of Wayne and State of Michigan, have invented a certain new, original, and ornamental Design for Perfume-Holders, of which the following is a specification, reference being had therein to the accompanying drawings, forming part thereof, in which the figure is a perspective view.

I claim:

The ornamental design for a perfume holder, substantially as shown.

GRANT BEST.
